UNITED STATES PATENT OFFICE.

EDWIN HENRY REIBER, OF WEST WEBSTER, NEW YORK.

EMBOSSING MACHINE.

Application filed February 20, 1923. Serial No. 620,271.

To all whom it may concern:

Be it known that I, EDWIN H. REIBER, a citizen of the United States, and a resident of West Webster, in the county of Monroe 5 and State of New York, have invented a new and Improved Embossing Machine, of which the following is a full, clear, and exact description.

This invention relates to improvements 10 in embossing machines, and has particular reference to a machine for embossing wood slabs or panels especially used in building bird houses, such as disclosed in my Patent Number 1,185,345, dated May 30th, 1916.

15 In the construction of houses such as described in the above patent, it has been customary to employ sassafras and red cedar, both of which woods are of the bark bearing type. It has further been found that the 20 use of these woods is not essential in constructing the houses and may be dispensed with in lieu of some other timber having the appearance of being bark bearing.

An object of the present invention is to 25 provide an improved machine which may be utilized to char a slab of wood in such manner that the same will be given antique grain and wood bark effects such as in sassafras wood.

30 Another object is the provision of improved means for positioning a slab of wood with respect to the embossing roller and feeding the slab thereto whereby the embossing operation is facilitated.

35 A further object is to feed a slab of wood into direct contact with a rotatable embossing element by the cooperation of said element with other means having a relative movement with respect to said element.

40 A still further object is the provision of a rotatable embossing roller having direct contact with a slab of wood to emboss the same and which is heated by a flame projected into one end thereof.

45 The above and other objects will appear more clearly from the following detail description, when taken in connection with the accompanying drawings, which illustrate a preferred embodiment of the inventive idea.

50 In the drawings—

Figure 1 is a front elevation of the machine, partly in section, and taken on the line 1—1 of Figure 2;

Figure 2 is a side elevational view taken on the line 2—2 of Figure 1; 55

Figure 3 is a section on the line 3—3 of Figure 1;

Figure 4 is a section on the line 4—4 of Figure 1; and

Figure 5 is a fragmentary plan view of 60 one of the slabs showing the result of the embossing operation.

Referring more particularly to the accompanying drawings, the numeral 10 indicates the main frame which includes a pair 65 of spaced vertical members 11, preferably in the form of I-beams, as shown in Figure 4. Associated with the main frame is an auxiliary frame 12, which is movable longitudinally of the beams 11 in a vertical 70 direction and supported in connection therewith by means of guide strips 13 secured along opposite vertical edges of the frame 12. To accomplish the vertical adjustment of the frame 12 a screw member 15 is 75 mounted for rotation in a cross piece 16 connecting the members 11, the threads of said screw member being engaged in the lower portion of the frame 12 so that upon rotation of the member 15 a vertical movement in either direction may be imparted to said frame 12. Extending laterally or 80 forwardly from one vertical edge of the frame 12 is a web 17 having its upper end formed with a horizontally disposed platform 18 arranged forwardly and to one side of the frame 12. A pair of parallel guide strips 19 are mounted upon the platform 18. These strips are arranged for adjustment toward and away from each other 85 by the provision of transversely extending slots 20 formed in the platform 18 so that the strips may be properly adjusted to receive therebetween the slab of wood 21, which is first mounted upon the platform 90 between said strips preparatory to the embossing operation. In the formation of these slabs the same are preferably provided with a flat surface and a convex surface, as illustrated in Figure 1, but it will be readily understood that said slabs may have other configurations without departing 95 from the spirit or scope of the present invention.

Journaled in the upper portion of the 105 frame 10 and extending transversely thereof

is a shaft 22 having a pulley 23 at one end thereof by means of which the shaft may be rotated, the opposite end of the shaft projecting beyond the adjacent side of the frame and having detachably mounted thereon an embossing roller support 24 including a plurality of arms 25, the free ends of which have detachably secured thereto the embossing roller 26. This roller is provided with an open end and, in the present instance, is shown as having an annular concave embossing surface 27, although it is to be expressly understood that this surface may be convex or flat. It will also be obvious that the roller may have a plurality of adjoining concave or convex embossing surfaces in the event that it is desired to emboss a slab of relatively greater width than the one shown in the drawings. Projecting from one side of the frame 10 and at the upper end thereof is a horizontally disposed supporting arm 28 which supports a hanger 29 adjustable longitudinally of said arm, said hanger in turn supporting a heating element 30, preferably in the form of a torch which is utilized to project a flame into the open end of the roller 26, whereby to adequately heat the same to accomplish the embossing operation when the slab 21 is brought in contact with the roller 26. The interior surface of the roller 26 may be provided with a lining 31 of any suitable heat retaining substance which will aid in maintaining the temperature of the roller constant.

A second shaft 32 is journaled in the upper end of the auxiliary frame 12 and has one end projecting from the side of the frame rearwardly of the platform 18. A pair of feeding rollers 33 are mounted upon said end of the shaft 32 and adjustable thereon toward and away from each other so as to properly engage slabs of different widths. The feeding rollers are positioned directly below the embossing roller 26 and have their peripheries arranged in the same plane with the supporting surface of the platform 18 so that as the slab 21 is pushed rearwardly from said platform the rollers 33 will engage the under surface thereof and feed the slab between the same and the embossing surface 27 of the roller 26. From the foregoing description, it will be obvious that the vertical adjustment of the frame 12 is provided for the purpose of accommodating various thicknesses of slabs between the rollers 26 and 33, thus permitting engagement of the surfaces of the slabs to be embossed with the embossing surface 27 regardless of the thickness of said slabs.

In order to facilitate the feeding of the slabs between the rollers 26 and 33, said rollers are driven in opposite directions by means of spur gears 34 and 35 carried, respectively, by adjacent ends of the shafts

22 and 32 and intermeshing with gears 36 and 37. The latter two gears are carried by an arm 38 pivoted at 39 to a vertically disposed plate 40 supported by the adjacent side of the frame 12, the gear 37 being concentric with said pivot and at all times in engagement with the gear 35. The gear 36 is arranged adjacent one end of the arm 38 so that when said arm is swung about its pivot 39 the gear 36 may be adjusted toward and away from the gear 34. The plate 40 is provided with an arcuate slot 41 through which extends a pin 42 carried by the arm 38, a wing nut or other fastening device 43 being threaded upon said pin and engageable with said plate to retain the arm 38 in various adjusted positions. By reason of this construction, it will be obvious that the arm 38 may be adjusted to disengage the gear 36 from the gear 34 to stop the rotation of the shaft 32 and, consequently, of the feeding rollers 33 and also that when a vertical adjustment of the frame 12 is made with a consequent movement of the gear 35 toward or away from the gear 34, an adjustment of the arm 38 may be accomplished to properly intermesh the gears 34 and 36 so that the shaft 32 may be rotated.

In the operation of the machine, a slab 21 is first placed upon the platform 18 between the guide strips 19 and then forced rearwardly to engage the under surface thereof with the peripheries of the feeding rollers 33 and the upper surface thereof with the embossing surface 27 of the roller 26. The rollers 26 and 33 being driven in opposite directions will cooperate to withdraw the slab from the platform 18 and the heat applied to the embossing surface 27 will be transmitted to the upper or convex surface of the slab 21 and char said surface as the same is passed beneath the roller. The design of the embossing surface 27 may be made to produce antique grain and bark effects, such as found on sassafras wood and after this design has been transferred to the upper surface of the slab the charred wood is brushed off and the raised portions of the surface sanded, leaving the finished product. By charring or burning the surface in the manner herein described it has been found that considerable is added to the durability of the article.

What is claimed is:

1. In an embossing machine, a roller having an embossing surface and an open end, means for feeding a slab into engagement with said embossing surface, and a heating element arranged to project a flame into the open end of said roller to heat the same.

2. In an embossing machine, a roller having an embossing surface and an open end, means for feeding a slab into engage-

ment with said embossing surface, a heating element arranged to project a flame into the open end of said roller to heat the same, and a heat retaining lining for the interior of 5 said roller.

3. In an embossing machine, a main frame, an auxiliary frame supported thereby and movable longitudinally with respect thereto, a platform carried by said 10 auxiliary frame, a shaft movable with said auxiliary frame, a gear carried by said shaft, feeding rollers also carried by said shaft in juxtaposition to said platform, a second shaft carried by the main frame, an 15 embossing element supported by said second shaft in cooperative relation with said feeding rollers and between which an article to be embossed is fed from said platform, a gear carried by the second shaft, and intermediate 20 gearing supported by said auxiliary frame and cooperating with the gear carried by said shaft, a portion of said gearing being adjustable relative to the gear carried by the second shaft and capable of 25 being constantly meshed with the gear carried by said second shaft when said auxiliary frame is moved relative to the main frame.

4. In an embossing machine, a main 30 frame, an auxiliary frame supported thereby and movable longitudinally with respect thereto, a platform carried by said auxiliary frame, a shaft movable with said

auxiliary frame, a gear carried by said shaft, feeding rollers also carried by said 35 shaft in juxtaposition to said platform, a second shaft carried by the main frame, an embossing element supported by said second shaft in cooperative relation with said feeding rollers and between which an article to 40 be embossed is fed from said platform, a gear carried by the second shaft, an arm pivotally connected to said auxiliary frame, and gearing carried by said arm and capable of meshing with the gears carried by said 45 shafts irrespective of movements of said auxiliary frame relative to the main frame.

5. In an embossing machine, a rotatable shaft, an embossing roller carried thereby, a second shaft movable toward and away 50 from the first-named shaft, feeding rollers carried by the second-named shaft and movable therewith into and out of cooperative relation with respect to said roller, gears carried by said shafts, and 55 other gears interposed between the first-named gears for imparting rotation of the first-named shaft to the second-named shaft, one of the latter gears being adjustable relative to the other gears and 60 capable of being constantly engaged with a gear carried by one of said shafts when said second-named shaft is moved toward and away from the first-named shaft.

EDWIN HENRY REIBER.
